WINDOW DEVICE

Application filed May 26, 1930. Serial No. 455,634.

This invention relates to improvements in window devices, and the object of these improvements are as follows; to supply an all metal window frame for a removable tilttable and adjustable ventilating window, the frame having means for discharging or draining outwardly rain or moisture to prevent entrance thereof into the building; to provide means for holding the tilttable window in different positions of open adjustments; to supply other means for stopping the window when fully opened to hold it releasably in that position; to furnish releasable fastening means for holding the window in its closed position, and to supply a channeled metal casing for the peripheral edge of the window pane employed as said window. Other improvements will be hereinafter shown and described.

The invention is described and claimed as follows, and illustrated by the accompanying drawing, wherein Fig. 1 is an elevation of the front face of the assembled window frame and window with accessories, showing the window fully closed and releasably secured in that position, with parts broken away. Fig. 2 is a medial vertical cross section thereof with window opened. Fig. 3 is a top plan thereof, with parts in horizontal section, and Fig. 4 is a detail perspective view of one of the side wings as detached from the window frame. Fig. 5 is a section of Fig. 1 on the broken line 5—5.

This invention is not restricted to the precise construction and arrangement of parts herein shown and described, nor to the various details thereof, as the same may be modified or rearranged in various particulars without departing from the spirit and scope of the invention, one practical embodiment of which has been herein illustrated and described without attempting to show all of the various forms and modifications in which the invention might be embodied.

This invention may be applied for use to any housing structure, but as shown herein, is particularly appropriated for such buildings, as barns, animal and poultry houses or the like.

In this invention the glass single pane win-

dow 15 of rectangular shape has its peripheral edge covered and protected by an inwardly channeled metal casing 14. This takes up wear and jar to save the margin of the glass from breakage by knocks or abrasions while being mounted or adjusted in position in opening or closing it relative to its housing or window frame. The latter consists of an all metal hollow frame to conform to said window, being of angular section, of which a flange part 1 therearound in one plane contacts with the outer face of a building structure, as shown at 3 in Fig. 2, the inwardly directed part or flange 2 whereof is fitted in a rectangular opening in said building to extend therebeyond, and having this extending part crimped at 6 at the top and sides to have the crimp opened outwardly.

The lower part or sill of the flange 2 has a raised margin 5 closed at the ends and which constitutes a channel or troughed seat or bearing for the lower edge of the window casing 14 (see Fig. 2). The window 15 may therefore be swung open from said window frame, and when shut its casing 14 fits snugly against the frame part 6 sealingly, so that rain, moisture or dust are prevented from seeping into or entering the building 3, and such moisture drains outwardly over the sill 2 without said window.

The numeral 11 denotes a pair of triangular side wings or walls having flanges along rear and forward edges at 11' and 13, the word "forward" indicating the window and its framing as viewed from within the building 3. Along the upper edge of each wing 11 a part 12, of triangular shape projects towards the like part on the other wing and has at the rear a depending part or flange 12' interrupted by a rectangular notch 12a. Each wing 11 is assembled with the window frame in the following manner. The rear vertical flange 11' is slipped downwardly into the open crimp of side element 6 and until the depending flange 12' is seated (see Fig. 3) in a cut away space indicated at 10 in the adjacent end of the top crimp or fold 6 of the frame 1 and 2. The notch 12a is provided to fit over a projection 9 on a sleeve 7 secured on the part 2.

The sleeve 7 has a rod 16 traversing it to have projecting terminations bent into cranks 17. As shown in Fig. 1, when the window is closed, these cranks can be rocked 5 downwardly, to clamp the upper end of the window against the frame tightly. The middle part of the sleeve 7 has a projection 8 overlapping the frame part 2 and secured thereto. This middle part of the sleeve has 10 a portion cut away to seat a sleeve part 18 of a forwardly projecting arm 20 on the rod 16, rockingly. The arm 20 has a plurality of downwardly opening crimps 21 (see Fig. 2), a terminal upward bend at 22, and a loop 23 15 is fastened on said terminal including a looped weight 24 secured therein. A finger-piece 19 is fastened on the middle of the casing 14 at the top of the window, for convenience in pulling or tilting the window 15 20 open, when the clamping cranks 17 are rocked to releasing position. When the window 15 is opened, it may be held releasably in an adjusted tilted position, by dropping the arm 20 to seat the upper casing part 14 25 within one of the crimps 21.

The numeral 11 denotes the side wings above referred to, and when the window 15 is tilted forwardly to its full extent it engages the flanges 13 which are of double 30 thickness by folding, and is stopped thereby, the arm bend at 22 then being swung down to engage the window casing 14, thus locking the window in its opened position, releasably. The wings 11 therefore serve not 35 only to support the window in this position, but also act as side walls which with the window deflect entering air into an upwardly moving current into the building 3, for proper ventilation and air circulation 40 therein. Bars 4 are fastened on the inner face of the wall 3 to embrace the top and sides of the frame part 2 and at the sides the wings 11 as stops for both upon said wall.

This type of window and framing, with 45 accessories, is particularly adapted for use in animal housing, the construction being all metal except the glass pane 15 (which may be of other material if desired), and hence is cheap, economical, light, easily assembled 50 and disassembled for storage, or transportation. The arm 20 is kept in place against the window by the weight 24, against accidental displacements, and when the window is closed, the arm with its weight, drops and 55 assists in fastening the window.

Having described this invention, what is claimed as new, and desired to be secured by Letters Patent, is:

1. A window device, comprising in combination, an apertured wall, an apertured window frame, the said frame fitting said aperture with outer flanges contacting sealingly the outer face of the wall therearound, an imperforate window fitting in said 60 frame to swing from the bottom away

from the frame, means movably connected to said frame engageable with the window releasably to hold it in differently adjusted open positions, side wings detachably mounted on the sides of the frame slidably at opposite sides of the window and side and top bars secured on said wall as stops thereon for said wings and said frame respectively. 70

2. A window device, comprising in combination, an apertured sheet metal window frame having an outer circumferential flange to contact and peripherally cover the joint of an apertured structure in which the window frame is mounted, said frame having inwardly directed flanges, at an angle to said first mentioned flange, the frame having a channeled lower sill, a window having its lower end tiltingly mounted in the channel of the sill to overlap said frame aperture, whereby when the window is closed moisture is deflected outwardly of said structure from the frame and window, imperforate side wings with parts slidably mounted on the frame removably to project inwardly at opposite sides of the window having their outer edges inwardly flanged to serve as stops for the window when swung open against them, and means for swingingly releasably clamping the top corners of the window to the frame in closed position. 80

3. A window device, comprising in combination, an apertured metal window frame having a longitudinally channeled bottom sill, a window tiltingly seated in the channel of said sill to close the frame aperture, means for limiting the extent of tilting movement of the window, and a device hinged to said frame and having a swinging catch and rocking end cranks to respectively hold the window in either its fully opened or in its closed position. 95

4. A window device, comprising in combination, a hollow sheet metal window frame, having side wings detachably mounted thereon with inwardly directed stop flanges, a window tiltingly mounted in said frame to swing to fully opened position against said stop flanges, and an arm hingedly mounted on the upper part of the frame and weighted at its free end, said arm having a plurality of transverse crimps to engagingly fit upon the upper edge of the window, to releasably retain it in a desired position of open adjustment, and having fixed thereon at opposite sides to move therewith angularly directed clamping fingers to releasably secure the top of the window in place when closed. 110

5. A window device, comprising in combination, a hollow window frame, a window tiltingly mounted at its lower end thereon, 125 means for adjustably supporting the window in different tilting adjustments, a sleeve bearing on the upper part of said frame, and a rod rockingly mounted in said sleeve having end cranks to engage both opposite upper cor- 130

ner parts of the window when closed to fasten it in evenly closed position, releasably.

6. In a window ventilator device, a stationary section around a window opening in a fixed structure, said section having at the lower end a bearing seat, a window sash whose lower end is tiltably mounted in said seat, and wings supported on the stationary section without the side edges of the window sash,
5 each wing being bent to have a depending triangular wing body diminishing downwardly and having an inturned rim on its outer edge, and to have an upper part extending angularly inwardly to brace and support
10 each wing being bent to have a depending triangular wing body diminishing downwardly and having an inturned rim on its outer edge, and to have an upper part extending angularly inwardly to brace and support
15 the said body part.

7. In a window ventilator device, a stationary section around a window opening in a fixed structure, said section having at the lower end a bearing seat, a window sash
20 whose lower end is tiltably mounted in said seat, wings supported on the stationary section without the side edges of the window sash, each wing being bent to have a depending triangular wing body diminishing downwardly and having an inturned rim on its outer edge, and having an upper brace portion extending inwardly, and fastening means mounted movably upon the device
25 adapted to releasably secure said window sash
30 in any adjusted position of tilting.

In testimony whereof we affix our signatures.

JOSEPH BURLEIGH CLAY.
LANCELOT ROYCE WILSON.
